UNITED STATES PATENT OFFICE.

FRANK SOLEY, OF PHILADELPHIA, PENNSYLVANIA, ASSIGNOR, BY MESNE ASSIGNMENTS, TO THE YALE & TOWNE MANUFACTURING COMPANY, OF STAMFORD, CONNECTICUT, A CORPORATION OF CONNECTICUT.

COMBINATION LOCK.

Application filed March 25, 1925. Serial No. 18,166.

My invention relates to certain improvements in combination locks, of the type used on locker and cupboard doors.

One object of the invention is to construct a combination lock so that the bolt can be projected and held positively in the projected position.

A further object of the invention is to provide rotary means for projecting and reTRACTING the bolt, and means for locking the dog in engagement with the tumblers when the bolt is reTRACTED.

A still further object of the invention is to improve the construction of the dial plate and the knob and to provide an adjustable connection between the knob and the mechanism within the lock casing.

The invention also relates to certain details which will be described hereinafter.

20 In the accompanying drawings:

Fig. 1 is a face view of my improved lock, the cover plate and change tumblers being removed, and showing the bolt reTRACTED;

25 Fig. 2 is a view, similar to Fig. 1, showing the bolt projected and the bolt and dog locked;

Fig. 3 is a sectional elevation showing the connection between the operating knob and the mechanism within the casing;

30 Fig. 4 is a perspective view of the bolt;

Fig. 5 is a perspective view of the cam plate;

Fig. 6 is a perspective view of the pin tumbler;

35 Figs. 7, 9 and 11 are views of the washers that separate the tumblers;

Figs. 8, 10 and 12 are views of the change tumblers;

Fig. 13 is a view of the carrier tumbler;

40 Fig. 14 is a perspective view of the spindle;

Fig. 15 is a perspective view of the knob; and

Fig. 16 is a detached sectional view of the 45 dial plate, barrel and associated parts.

The casing 1 is made of sheet metal, punched and pressed into shape. A hollow stud 2 is secured to the casing and is shouDERED, as shown in Fig. 3. Mounted on the 50 stud is a cam plate 3 and a pin tumbler 4 having a pin 5. Between the cam plate and the casing is a bolt 6, which is made as shown in Fig. 4. The bolt has a thickened portion, which is projected beyond the casing, as

shown in Fig. 2. In this portion of the bolt 55 is an elongated slot 7, of a width equal to the diameter of the stud so that the stud acts as a guide for the bolt. On the bolt is a pin 8. The back of the thickened portion of the bolt is curved, as at 9, to form a bearing 60 surface for the cam plate 3. The cam plate 3 projects between the bearing surface 9 and the pin 8. When the cam plate is moved in the direction of the arrow, Fig. 1, it bears against the surface 9 and projects the bolt. 65 When the bolt is fully projected, the cam plate is directly back of the bolt and locks it in the projected position, as in Fig. 2. When the cam plate is moved in the opposite direction, it strikes the pin 8 and reTRACTS the bolt. 70

On the cam plate 3 is a lug 10, which is shaped to fit slots 11 in the washers 12, 12^a and 12^b. Three washers are shown in the present instance. Mounted on the stud 2 75 and alternating with the washers are change tumblers 13, 14 and 15, shown in Figs. 8, 10 and 12. Each tumbler has a segmental slot for the pin 5 and each tumbler has a notch in its periphery to receive the dog 16, which is pivoted at 17 to the cam plate 3. A spring 18 acts to force the dog towards the tumblers so that, when all of the notches are in alignment, the dog enters the notches and locks the cam plate to the tumblers. 80

85 A spindle 19 extends into the stud 2 and has a pin 20, which enters slots 21 in a carrier tumbler 22 that is mounted on the pin. This carrier tumbler is located between the inner end of the stud and the cover plate 1^a 90 and has a series of notches in its periphery and a series of segmental slots, as shown in Fig. 13. One side of each notch is beveled so that, when the bolt is projected and the movement of the knob is continued, the dog 95 is forced out of the notches in the change and pin tumblers, at which time it is held in engagement with the end of a fence 23 on the casing 1 by the tumblers when they are turned to move the notches out of alignment 100 with the dog, as shown in Fig. 2.

When the bolt is being reTRACTED and while in the reTRACTED position, the dog rides on the curved portion of the fence 23, which holds the dog in the notches of the tumblers, as 105 illustrated in Fig. 1. The curved fence 23 is pressed from one of the side walls of the casing as shown in Fig. 1.

By the construction of the bolt and its operating cam plate, binding of the dog is prevented.

The dial plate 24 is secured to the outer side of the door 25 and screws or rivets attach both the dial plate and the lock casing to a door, in the present instance.

On the dial plate is a barrel 26, which is secured to the plate by riveting. This barrel has an internal flange 27, on one side of which is a click ring 28. On the opposite side is a plain washer 29. The knob 30 has a portion extending into the barrel 26, as shown in Fig. 3, and has a toothed flange 31, which engages the click ring 28.

The hub of the knob is grooved to receive a retaining ring 32, which secures the knob to the dial plate. The knob has a hole 33 to receive the spindle 19. On the spindle is a projection 34, which enters a groove in the knob, thereby insuring the turning of the spindle and the lock mechanism with the knob. The construction also allows for adjustment of the dial plate and the knob in respect to the lock casing to accommodate doors of different thicknesses.

I claim:

1. The combination in a lock, of a casing; a bolt, means, within the casing, for actuating the bolt, one of the means being a tumbler having a central opening and slots at each side of the opening; a spindle adapted to the central opening; a pin on the spindle extending into the slots so that, on turning the spindle, the tumblers are turned; a dial plate through which the spindle extends; a

projection on the spindle; and a knob having an opening to receive the spindle, the slot at one side receiving the projection, the arrangement of the parts being such that 40 the casing and dial plate can be adjusted to fit doors of different thicknesses.

2. The combination of a lock casing; a bolt in the casing; means, within the casing, for operating the bolt; a spindle projecting 45 from the casing and through the door; a dial plate having a hub secured to the outer side of a door and having a notched ring; and a notched knob arranged to click with the ring, said knob having an opening there- 50 in for the spindle and a slot at one side to receive a projection on the spindle, the inner portion of the knob being grooved to receive a retaining ring, whereby the withdrawal of the knob from the plate is prevented. 55

3. The combination in a lock, of a casing; a stud projecting within the casing; a cam plate pivotally mounted on the stud; a bolt 60 slidably mounted between the cam plate and the casing and guided by the stud, the bolt having a bearing portion for the cam; a pin on the bolt, said cam plate having a portion extending between the pin and the bearing on the bolt; a spring-actuated dog on the cam plate; notched tumblers pivotally 65 mounted on the stud; means for turning the tumblers; and a fence on the casing so located as to engage the dog when the bolt is projected, and to hold the dog in engagement with the tumblers when the bolt is 70 retracted.

FRANK SOLEY.
